UNITED STATES PATENT OFFICE.

HENRY F. GOLDSMITH, OF PHILADELPHIA, PENNSYLVANIA, ASSIGNOR TO FRIED-
BERGER-AARON MANUFACTURING COMPANY, OF PHILADELPHIA, PENNSYL-
VANIA, A CORPORATION OF PENNSYLVANIA.

GARTER-DISPLAY MEANS.

Application filed December 19, 1925. Serial No. 76,387.

To all whom it may concern:

Be it known that I, HENRY F. GOLDSMITH, a citizen of the United States, residing at Philadelphia, county of Philadelphia, and State of Pennsylvania, have invented a new and useful Improvement in Garter-Display Means, of which the following is a full, clear, and exact description, reference being had to the accompanying drawings, which 10 form a part of this specification.

My invention relates to the art of displaying garters and similar articles of manufacture. The objects are: to provide supporting means for the garters, or pairs of garters, that will permit them to be displayed, one above another, in such manner that each pair of garters will stand out clearly from the other pairs; and to provide garter supporting means to which the garters may be 15 readily applied and from which they may be readily removed. The invention comprises a primary or direct support for each garter or pair of garters and with which the garters are in stationary relationship, and a secondary support for a number of pairs of such 20 directly supported garters, the secondary support comprising an upright standard with which the garters and their primary supports are adapted to slidably engage; 25 the structures and relative arrangements and dimensions of the primary and secondary supports being such as to permit the garters to be displayed as above specified and to allow the garters to be slidably applied to 30 and removed from the secondary support with a substantial elimination of friction between the garters and such secondary support.

A preferred embodiment of the invention 40 is shown in the accompanying drawings, in which—

Fig. 1 is a front view of the complete display device with the garters applied thereto.

Fig. 2 is a section on the line 2—2 of 45 Fig. 1.

Fig. 3 is a horizontal section, on an enlarged scale, through the display device and one of the garters.

Fig. 4 is a front view of the standard that 50 comprises one of the elements of the display device.

Fig. 5 is a side view of one of the feet that are adapted to engage the standard and support it in an upright position.

The standard *a*, which is composed preferably of a flat strip of cardboard, is supported in an upright position by any convenient means. I prefer to provide the standard with a widened base portion *b*, which is slotted from its bottom edge upward and is engaged by two similarly slotted rearwardly extending feet *c*, the base and feet thereby supporting the standard. The standard may, however, be suspended from a hook adapted to engage the hole *d*, and be unsupported at the bottom.

Each garter *x*, or each pair of garters, is adapted to be supported on a spreader *e*, which is composed preferably of a flat strip of cardboard *e*. The strip should be slightly longer than half the garter's normal circumference (that is, its circumference when not under tension). Thereby, the garter, when slipped on the spreader, will be under a slight tension, thus insuring against its accidentally slipping off.

The width of the standard *a* should be substantially less than the length of a spreader *e*. The length of the standard *a* should be multiple times the width of a spreader *e*.

To display a number of pairs of garters, the same are applied to a corresponding number of spreaders, and the spreaders, with their applied garters, are successively slipped over and down along the standard, being finally arranged one above the other. Alternate spreaders may be pulled respectively to the left and right so as to make an effective display of the garters.

It will be observed that each pair of garters is supported both by a primary support (a spreader *e*) and a secondary support (the standard *a*); that when thus doubly supported the spreader and one half of the garter extends on one side of the standard, while the other half of the garter extends on the other side of the standard; that any pair of garters may be readily removed or applied to the standard by a slipping or telescoping movement; and that the elasticity of the garters tends to slightly bend the spreader, as shown in Fig. 3, thereby almost eliminating friction between the standard and the portion of the garter's circumference that is immediately adjacent the standard.

Having now fully described my invention,

what I claim and desire to protect by Letters Patent is:

A garter display device comprising a plurality of separate spreaders each composed of a flat strip over which a garter is adapted to be slipped and on which the garter is adapted to be held, and a standard composed of a flat strip which the several spreaders and the garters carried thereby are adapted to slidably engage, the length of the standard being multiple times the width

of a spreader, and the spreaders being of a length substantially greater than the width of the standard so as to permit the spreaders and garters to project laterally beyond the standard.

In testimony of which invention, I have hereunto set my hand, at Philadelphia, Pennsylvania, on this 15 day of December, 1925.

HENRY F. GOLDSMITH.
